UNITED STATES PATENT OFFICE.

CHARLES W. ERVIN AND WILLIAM E. MACGUIRE, OF ANACONDA, MONTANA.

MIXER.

1,312,240.

Specification of Letters Patent.

Patented Aug. 5, 1919.

Application filed February 26, 1919. Serial No. 279,376.

To all whom it may concern:

Be it known that we, CHARLES W. ERVIN and WILLIAM E. MACGUIRE, citizens of the United States, residing at Anaconda, in the county of Deer Lodge and State of Montana, have invented certain new and useful Improvements in Mixers, of which the following is a specification, reference being had to the accompanying drawings.

10 This invention relates to the art of fuel homogenizers, and particularly to a device of this kind adapted especially for use in internal combustion engines and carbureters of automobiles.

15 The invention in its broadest aspect aims to provide an improved device for mixing the fuel, thereby increasing its combustibility, in order to render each charge more efficient, prior to entering the combustion 20 chamber through the intake manifold.

Further it is the aim to provide means located between the intake manifold and the carbureter, and being intermittently revolvable under the influence of the fuel or charges, 25 incident to the intake strokes of the piston of the engine, and in which means revoluble screening devices are included, not only to screen the fuel, but also acting to break or disintegrate the particles, thereby insuring 30 a finer and superior combustible fuel.

The invention further aims to afford an additional revoluble member in advance of the screening devices to further break the 35 particles of the fuel, imparting a fanning action thereon, which will agitate and thoroughly mix the charge.

The invention further aims to provide supporting means, on which the intermittent revolvable means is supported, there being 40 means afforded, such as cup-shaped agate thrust bearings for the supporting means, whereby the intermittent revolvable means may easily and freely rotate under the influence of the fuel in its passage through 45 the manifold.

The design of the invention at the present time has been found practical. However, in reducing the invention to a practical form for commercial purposes, alterations in the 50 minor details may be found necessary, and the right to these alterations is claimed, provided they are warranted by what is claimed.

The invention comprises further features 55 and combinations of parts, as will be here-

inafter set forth, shown in the drawings and claimed.

In the drawings:

Figure 1 is a view in elevation and partly in section of an intake manifold and the portion of a carbureter, showing a casing interposed therebetween, and the fuel homogenizer contained in the casing.

Fig. 2 is a detail view in section of the mixing device removed from the casing, showing the casing of the mixing device in section, and illustrating the supporting means for the mixing elements.

Fig. 3 is a cross-sectional view on line 3—3 of Fig. 2.

Fig. 4 illustrates collective views of the screen member and the retainer therefor and the intermediate bands, and the collars.

Fig. 5 is an enlarged detail view of one of the cup-shaped agate thrust bearings.

Referring to the drawings 1 designates an intake manifold and 2 a portion of a carbureter. The manifold is provided with a cylindrical extension 3 having an annular flange 4 at its lower end. An elbow casing 5 is interposed between the extension 3 and the carbureter, and one end of the elbow casing is supplied with an annular flange 6, through which and the flange 4 suitable bolts 7 having nuts pass, thereby securing the adjacent flanges together, and supporting the elbow casing in position.

It is to be observed that the elbow casing at a point adjoining its flange 6 is provided with a depression 8. On the interior of the elbow casing an annular flange 9 is formed, an auxiliary cylindrical casing 10 is arranged in the extension 3 telescopically and likewise in the elbow casing 5, engaging upon the flange 9. The auxiliary cylindrical casing 10 has an annular flange 11, which engages the recess 8, thereby holding the casing 10 firmly in position. It is obvious that when the extension and the elbow casing are separated, the casing 10 may be inserted in the elbow casing whereby its flange 11 may engage the annular depression 8, after which the elbow casing may be bolted in position, the other end of the casing 10 protruding telescopically into the extension 3.

Secured by cap screws or the like 12 on one end of the casing 10 and transversely thereof are radial arms 13 of the collar 15, the opening 14 of which is threaded. The other end 110

of the casing 10 has radial transverse bars or strips 16 integral therewith. These strips 16 have their inner ends connected to a collar 18, which has its opening 17 threaded. 5 It is seen that the openings 14 and 17 are axially alined, and threaded axially into said openings are hollow shank screws 19 and 20. The interiors of the shanks of the screws are designed for the reception of cup-shaped 10 agate thrust bearings 21 and 22. In order to retain the bearings in the shanks of the screws, the marginal edge portions of the shanks are upset as shown at 23, in order to overlie the marginal portion of the bearings. 15 These bearings are also axially alined, and are designed to receive the opposite ends of a shaft 24 constructed of suitable metal, preferably steel. Revolving with the shaft 24 is a sleeve 25, it being obvious that the 20 shaft 24 is capable of free revoluble movements in its axial bearings. One end of the sleeve is provided with radial fan blades 26 oppositely pitched, so that incident to the influence of the fuel being drawn into the 25 manifold upon the intake stroke of the piston, revoluble movement will be imparted to the shaft, consequently the sleeve. Formed integral with the other end portion of the sleeve are radial arms 27, integral with 30 which is a depending cylindrical retaining wall 28. This casing 10 is constructed in two sections, and where its annular flange 11 is formed, the sections are joined. The section 29 of the casing 10 has its interior 35 larger in diameter than the interior of the section 30. Hence, a shoulder 31 is provided on the interior of the casing 10. By this construction, it is clear that the parts contained in the casing 10 can be easily assembled and arranged in place. The sleeve 25 constitutes a hub for the retainer 28. Arranged in the retainer wall is a plurality of 40 fuel screening members 32 arranged in series. These screening members have annular portions 33, which extend in the same direction and are concentric. Arranged between the screening members are annular bands 34, thereby holding the screening member spaced, and in position. In order 45 to arrange the screening members in the retainer they are provided with central openings for the reception of the end of the sleeve, which constitutes the hub of the retainer. Collars 35 are arranged telescopically upon the hub of the retainer, and intermediate the screening members, in order 50 to additionally hold the same spaced, and at the same time preventing dishing. Adjacent the lowermost collar 35, and in order to 55 support the collars a holding collar 36 is fastened to the end of the sleeve. This holding collar 36 is supplied with radial arms 37, which are integrally connected to an annular ring 38, which engages the lowermost band 60 65 34, so as to hold the bands and the screening

members in their proper positions. The collar 36 is threaded on the sleeve, so that the series of collars and the screening members may be clamped against the radial arms 27. 70

On the intake stroke on the piston of the engine, the air that is drawn into and through the manifold of the engine, imparts revoluble movement to the fan blades, and since this movement is exceedingly 75 rapid, the fuel or charge is drawn from the carbureter into the casing 10, passing rapidly through the several screening members, and since the screening members are also rapidly revolving the fuel or charge is thoroughly 80 mixed and broken up into the finest possible particles, and at the same time is mixed with the proper portion of air. This action insures a superior combustible charge for 85 internal combustion engines, increasing the power and efficiency of the engine and at the same time reducing fuel consumption, thereby cutting down the operating expenses. 90

The invention having been set forth, what is claimed as new and useful is:

1. In a fuel mixing mechanism, the combination with a freely revoluble shaft, of a sleeve rotatable therewith, a mixing mechanism retainer depending from the sleeve, the end of the sleeve opposite the retainer being 95 provided with blades, fuel mixing means in the retainer, and a casing for the aforesaid parts, provided with bearings for the shaft, said mixing means comprising a plurality of spaced screening elements having annular 100 portions, spacing bands therefor, engaging the annular portions of the screening elements, collars on the sleeve additionally spacing the screening elements and preventing them from dishing, and means for clamping the parts of the mixing mechanism in 105 position.

2. In a device for mixing fuel, the combination with a casing having its opposite ends open, and provided with axially alined 110 supporting bearings, of a shaft revoluble in said bearings, a sleeve rotatable therewith, the upper end of the sleeve having blades, the lower portion of the sleeve having a depending retainer open at both ends, one end 115 of the retainer having radial arms, a plurality of screen members having annular portions, super-imposed and spaced, bands telescoping within the annular portions of the screen members, collars mounted on the 120 sleeve between the screen members preventing dishing of the screen members, and means on the lower end of the sleeve for clamping the aforesaid parts together, the uppermost screen member abutting said rotary arms. 125

3. In a fuel mixing device, the combination with a revoluble sleeve provided with radial arms, of a cylindrical retainer having diametrically opposite portions of its wall 130

- depending from said arms, a supporting device detachably carried on the lower end of the sleeve, a plurality of fuel mixing elements super-imposed and spaced and interposed between the arms and the supporting device at the lower end of the sleeve, said mixing elements having annular portions, means engaging within said elements and clamping their annular portions in contact with the wall of the retainer, means on the sleeve interposed between said elements for holding the central parts of the elements against dishing, and a holder for the revoluble sleeve.
- 15 4. In a mixing device, the combination with a revoluble sleeve, of a plurality of fuel mixing elements mounted on the sleeve super-imposed in spaced relation to each other and provided with marginal portions, means engaging within and exteriorly of the portions, to hold the elements spaced, the means exteriorly of the portions being carried by the sleeve, and means on the lower end of the sleeve for supporting the interior 20 means in position.
- 25 5. In a mixing device, the combination with a revoluble sleeve, of a plurality of fuel mixing elements mounted on the sleeve super-imposed in spaced relation to each other and provided with marginal annular portions, means engaging within and exteriorly of the annular portions, to hold the elements spaced, the means exteriorly of the annular portions being carried by the sleeve, means on the lower end of the sleeve for supporting the interior means in position, means fitting on the sleeve and interposed between the elements for holding their central parts against dishing, and a holder open at both ends and provided with bearings, and a member mounted in the bearings and carrying the sleeve.

In testimony whereof we hereunto affix our signatures in the presence of two witnesses.

CHARLES W. ERVIN.
WILLIAM E. MACGUIRE.
